UNITED STATES PATENT OFFICE.

HENRY C. OSBORN, OF CLEVELAND, OHIO, ASSIGNOR TO THE AMERICAN MULTIGRAPH COMPANY, OF CLEVELAND, OHIO, A CORPORATION OF OHIO.

INKING-ROLLER.

1,030,917.

Specification of Letters Patent.

Patented July 2, 1912.

Application filed May 24, 1909. Serial No. 497,828.

To all whom it may concern:

Be it known that I, HENRY C. OSBORN, a citizen of the United States, residing at Cleveland, in the county of Cuyahoga and State of Ohio, have invented a certain new and useful Improvement in Inking-Rollers, of which the following is a full, clear, and exact description, reference being had to the accompanying drawings.

10 The object of this invention is to provide a very simple and efficient inking roller which is formed to work up and distribute the ink, thus doing away with the necessity of an additional longitudinally moving distributing roll. My inking roller is adapted to have the ink applied directly to it, whereby it also takes the place of an inking fountain or disk.

20 My inking roller is well adapted to cooperate with a small office printing press, for example of the type of the multigraph or gammeter printer. The invention is illustrated herein as applied to such construction, and its essential characteristics will be 25 clear from the following explanation of such illustration and from the appended claims.

30 In the drawings, Figure 1 is a plan of a portion of a rotary printing drum with my inking roller and an intermediate transferring roller coöperating therewith; Fig. 2 is an end view of such parts; Fig. 3 is a longitudinal section through my inking roller; Figs. 4 and 5 are transverse sections of the same on the correspondingly numbered lines 35 of Fig. 3.

40 My inking roller, as shown, consists essentially of a body portion A, in the form of a mutilated cylinder, and one or more segments B B, which are set into recesses in the surface of the member A,—the outer surface of the member and segments comprising a circular roller, as appears from Figs. 4 and 5.

45 In the embodiment shown, the body A of the roller is provided at its ends with bushings C and C', by which it is journaled rotatably on the rod or shaft D. This shaft is shown as mounted in the brackets E and E', which are secured to the frame plates 50 F and F' of the printing machine. On the shaft, near its center is provided a double crown cam G which is made by a groove g in a sleeve held against rotation on the shaft. The segmental members B B, of which two 55 are shown, have inwardly extending arms b,

which have eyes embracing the shaft D. Each segmental member has also an inwardly projecting lug b' on which is mounted a roller H occupying the groove g.

The result of the above construction is that if the roller be rotated relatively to the shaft the partially cylindrical members B B will be automatically moved, one in one direction, and one in the other to continually distribute the ink. Suitable space, as a, in 60 the body A allows for such movement of the inwardly extending arms b.

To cause a relatively slow travel of the rollers H in the groove g, while the inking roller itself is rotating at a greater speed, I 70 rotate the shaft D in the same direction as the roller A, but at a different speed. This differential may be varied according to circumstances and operates to gradually move the segmental members B backward and forward 75 during the continuous rotations of the inking roller.

The gearing shown for causing the differential rotation of the inking roller and shaft is very simple and comprises a gear K on the roller meshing with a gear L on the intermediate roller N, which latter meshes with the gear P on the drum R of the printing machine, while rigid on the shaft n of the roller N is a gear J meshing with the gear 80 I on the shaft D. The gears J and I have a different speed ratio from the gears L and K. A set screw S is shown as screwing into the bracket E and occupying a groove d' in the shaft, preventing its longitudinal shifting 85 while allowing its rotation.

90 The drum R, as shown in Fig. 2, may be formed with rails to carry parallel lines of individual grooved type, after the manner of the multigraph. When the drum is rotated, such type come in contact with rotating roller N, made of composition, and receive ink therefrom, the roller N being continuously and evenly inked from my fountain roller described. The ink is supplied in a 95 paste form by an ink knife or otherwise to my fountain roller and is worked up by the shifting of the members B and B thereof.

99 My fountain roller may be very easily taken apart for cleaning and reinstalled. The loosening of the screw S allows the shaft D to be drawn out of the brackets E E'. This allows the removal of the roller as a whole. It also frees the segmental members and the sleeve G. To reinstall the parts, the 105 110

sleeve G is placed in the recess a' in the body A and the members B are put in place with the rollers H occupying the groove g. In this position, the eyes through the arms b 5 aline. The shaft is then projected lengthwise through the bearing E, the bushing C, the first set of arms b, the sleeve G, the second set of arms b, the bushing C' and the bracket E'.

10 In order to hold the sleeve G stationary with reference to the shaft, it is provided with a key g' (Fig. 4) which is adapted to occupy a key-way d extending along the shaft, from a point at the headside of the 15 sleeve to the free end of the shaft. Accordingly, after, the shaft has been passed through the eyes of the first arms b and abuts the end of the key g' , it is simply turned axially until its key-way alines with 20 the key when the shaft is shoved home and locked by the screws S. The composition roller N which forms the intermediate member between my fountain roller and the type is shown as having axial studs n, which are 25 mounted in eccentric bushings T carried in the corresponding brackets E-E'. These bushings have heads adapted to receive a wrench for their adjustment and they are locked by suitable screws as U.

30 It will be seen from the above description that my invention is extremely simple in construction and greatly reduces the number of parts required for an inking attachment. Moreover, it is very easily applied 35 and removed and may be taken apart for cleaning whenever desired.

Having thus described my invention, what I claim is:

1. The combination of a rotary printing 40 drum, an ink conveying roller coöperating therewith, and a fountain roller in contact with the conveyer roller and having a portion of its surface movable with reference to another portion, and means for longitudinally reciprocating such portions whereby 45 such mutually moving portions overlap each other longitudinally.

2. In an inking roller, the combination of a plurality of segmental surfaces of the 50 same radius which coöperate to make a roller, means for rotating said surfaces as a unit, means for moving one of the surfaces with reference to the other during a rotation.

3. The combination of a shaft, a cam 55 thereon, a roller rotatably mounted on the shaft, a shiftable member on the roller, having its exterior flush with the exterior of the roller, and a connection between said member and said cam.

60 4. The combination with a shaft, a mutilated roller mounted thereon, a segment of a

roller mounted in a recess in the mutilated roller to have its exterior flush therewith, a cam, and a connection between the same and the segment, whereby the segment is longitudinally shifted as the composite roller rotates.

5. The combination of a mutilated roller having an arc-shaped recess on its surface, an arc shaped plate mounted in said recess and having its exterior surface flush with the surface of the roller and having an inwardly projecting member, a cam, and a groove in the cam which said member occupies.

6. The combination in an inking roller, of a body portion having a partially cylindrical exterior, of a pair of recesses between the cylindrical portions and exteriorly flush with the roller surface, a pair of longitudinally movable segments mounted in said recesses, and means for shifting said segments in opposite directions as the roller rotates.

7. The combination in an inking roller, of a body portion having a partially cylindrical exterior, of a pair of recesses between the cylindrical portions, a pair of longitudinally movable segments mounted in said recesses and exteriorly flush with the roller surface, arms on said segments extending into recesses in the roller, and a supporting shaft 90 passing through eyes in said arms.

8. The combination with a printing member, of a rotatable inking roller therefor having two portions of its surfaces in the form of longitudinally shiftable segments separated by non-shiftable portions of the roller, and means for shifting said segments in opposite directions as the roller rotates.

9. In an inking attachment for rotary printing presses, the combination of a pair 100 of brackets, a shaft adapted to be mounted therein, a fountain roller and a transferring roller mounted in said brackets, said fountain roller being composite with one portion of its surface shiftable with reference to another portion, and means for moving such shiftable portions longitudinally with reference to each other.

10. The combination of a roller made up 110 of a plurality of relatively movable inking sections, and a cam for moving said sections, one with reference to the other as the roller rotates, and means for differentially rotating the cam and roller.

In testimony whereof, I hereunto affix my 115 signature in the presence of two witnesses.

HENRY C. OSBORN.
